DEVICE FOR INJECTING FLUIDS INTO THE SOIL

Filed May 19, 1939

UNITED STATES PATENT OFFICE

2,218,652

DEVICE FOR INJECTING FLUIDS INTO THE SOIL

Clarence H. McDannel and Clarence O. McDannel,
Caldwell, Idaho

Application May 19, 1939, Serial No. 274,599

4 Claims. (Cl. 47—49)

This invention relates to an injector or gun, and relates more particularly to a device of this nature useful in introducing weed destroying chemicals, fertilizers, etc., into the ground. A general object of this invention is to provide a simple, practical and effective injector of the character mentioned.

Another object of this invention is to provide a device for injecting fluid into the soil that is operable to discharge a measured or given quantity of fluid into the ground at a selected depth for the destruction of weeds, the fertilizing of plants, the destruction of gophers and moles, and for other purposes.

Another object of this invention is to provide a device of the character mentioned that may be regulated or adjusted to discharge any selected quantity of fluid at any selected distance below the ground surface.

Another object of this invention is to provide an injector of the character mentioned that is operable to discharge the fluid into the soil under a substantial pressure to assure the desired distribution of dispersion of the fluid in practically all kinds of soil.

Another object of this invention is to provide a device of the character mentioned that is entirely self-contained, embodying a needle or discharge element to be forced into the soil, a container for the fluid and a pump means operable by the operator to force measured quantities of the fluid into the earth.

Another object of this invention is to provide a device of the character mentioned in which the pump means is easily operated by a simple push or downward force.

A further object of this invention is to provide a device of the character mentioned that is simple and compact and light in weight, to be easily transported and operated.

A still further object of this invention is to provide a device of the character mentioned that will not become clogged or made inoperative by the entrance of soil or solid matter and will not drip or leak.

The various objects and features of our invention will be fully understood from the following detailed description of typical preferred forms and applications of the invention, throughout which description reference is made to the accompanying drawing, in which:

Fig. 1 is a side elevation of the device of the present invention with the plunger rod in its lowermost position. Fig. 2 is an enlarged central longitudinal detailed sectional view broken away

to show the principal parts of the device in section, the valve and plunger rod being shown in elevation, and Fig. 3 is a fragmentary longitudinal sectional view of a modified or alternative form of construction.

The gun or injector of the present invention may be said to comprise, generally, an elongate column or body 10, a container 11 on the body 10 supplying fluid thereto, a discharge member 12 on the body 10 to be forced into the soil, and pump means 13 in the body 10 for discharging measured quantities of the fluid from the member 12.

The column or body 10 carries the various other elements of the device and is an elongate tubular member or structure. In the preferred construction the body 10 comprises an upper section 14 and a lower section 15. A suitable handle 16 is provided on the upper end of the upper body section 14 to facilitate the carrying and operating of the device. In the case illustrated the upper wall portion of section 14 is curved or bent inwardly and the handle 16 projects laterally or horizontally in opposite directions from this constricted portion of the section 14. The handle 16

15 may be in the nature of rod stock or tubular stock welded to the body section 14. The lower end part of the upper section 14 is reduced in diameter for connection with the lower section 15. The lower end part of the upper section 14

20 is reduced in diameter for connection with the lower section 15. In the form of the invention being described the reduced lower portion of the section 14 is threaded in the upper part of the lower section 15 to connect the two body sections. A lock nut 17 is threaded on the section

25 14 to lock the sections 14 and 15 against relative threading. It is to be observed that the connection between the sections 14 and 15 is adjustable upon loosening of the nut 17. The lower body section 15 forms the barrel of the pump

30 means 13 as will be later described, and serves to carry the needle or discharge member 12. The body 10 just described is in a generally vertical position when the device is in use.

40 The container 11 is provided to hold the fluid to be injected in the ground. The container 11 may be proportioned to carry a substantial quantity of the fluid and is associated with the upper section 14 of the body 10 to supply the fluid 50 to its interior. In accordance with the broader aspects of the invention the container 11 may be secured to the body 10 in any selected manner. In the case illustrated the body section 14 passes vertically through substantially central

openings 18 in the upper and lower walls of the container 11 and welding 19 secures the container to the section 14 and seals off the openings 18. A filling opening in the upper wall of the container 11 is normally closed by a removable cap 20. One or more ports 21 are provided in the wall of the body section 14 to place the container 11 in communication with the interior of the body section. When the container 11 is secured to the body 10, as described above, it is preferred to space the container between the upper and lower ends of the section 14 and to arrange the container in concentric relation with the body. The container 11 is preferably cylindrical when mounted in concentric relation with the body.

The discharge member 12 is in the nature of a spike or needle secured to the lower end of the body 10 and designed to be forced into the earth to conduct the fluid downwardly and to discharge the fluid under pressure into the earth. The member 12 is an elongate tubular member arranged in aligned or concentric relation with the body 10. In practice the member 12 is considerably smaller in diameter than the body 10 to better enter the soil. The reduced member 12 may be connected with the lower end of the lower body section 15 in any suitable or practical manner. In the case illustrated a tapered portion 22 serves to connect the section 15 with the upper end of the member 12. A sharpened or pointed tip 23 is replaceably threaded on the lower end of the discharge member 12 and is designed to readily enter and penetrate the soil. The opening or longitudinal passage 24 of the member 12 is in direct communication with the lower end of the body section 15 and the tip 23 has a socket 25 communicating with the lower end of the passage 24. A plurality of circumferentially spaced discharge ports 26 is provided in the tip 23 to communicate with the socket 25. The ports 26 preferably face horizontally or laterally. The tip 23 is valued as will be later described.

In accordance with the invention the needle-like discharge member 12 is provided with a foot piece and stop 27 to facilitate the forcing of the member into the soil and to limit the distance the member may enter the soil. The stop 27 projects laterally from the member 12 and is shaped to be conveniently engaged by the operator's foot for the application of a down pressure. The foot piece and stop 27 is a flat, generally horizontal, member whose lower side is adapted to engage the ground surface to stop the downward movement of the member 12. In accordance with the invention the stop 27 is adjustable longitudinally on the member 12 so that the device may be adjusted or regulated to discharge the fluid at any selected depth. An opening 28 extends vertically through the stop 27 and slidably passes the member 12 whereby the stop may be shifted vertically along the member. A clamp screw 29 is threaded in a horizontal opening in the stop 27 and is adapted to clamp against the member 12 to hold or set the stop in any selected position. Upon loosening the clamp screw 29 the foot piece and stop 27 may be moved along the member 12 to the selected position.

The pump means 13 is actuated by the operator to force a given or measured quantity of fluid into the earth at each operation. The pump means 13 includes a tubular plunger 30 operable longitudinally in the tubular body 10. The plunger 30 is received in the body sections 14 and 15 with substantial clearance and packing is pro-

vided in the body to seal with the plunger. A packing assembly is held between the lower end of the body section 14 and an annular bead 31 on the section 15 formed by indenting the wall of the section 15. This packing assembly may comprise metal follower rings 32 engaged against the lower end of the section 14 and the bead 31 and an annular body of packing 33 is engaged between the rings 32. The packing 33 may be laminated or may be a solid piece. The packing 33 of course seals around the shiftable plunger 30 and seals with the internal wall of the body section 15. The packing assembly just described may be adjusted or compressed to effectively seal about the plunger 30 by loosening the nut 17 and further threading together the body sections 14 and 15. Thus the threaded connection between the body sections 14 and 15 constitutes a means for compressing or adjusting the packing for sealing about the plunger 30. It is to be observed that the portion of the body section 15 below the packing means forms a pump chamber or displacement chamber C.

The pump means 13 further includes a rod 34 secured to the plunger 30 and extending upwardly through the body 10 to the upper end of the device. The upper portion of the plunger 30 may be reduced to receive the end part of the rod 34 and the rod may be welded to the plunger 30 at 35. The rod 34 passes upwardly through the body 10 with considerable clearance and projects upwardly beyond the upper end of the body section 14. A tubular extension or guide 36 is provided on the upper end of the body section 14 and slidably passes the plunger rod 34 to guide the rod and the plunger 30. The guide 36 may be melded or otherwise fixed in the reduced upper part of the body section 14. A stop collar 37 is welded or otherwise fixed to the rod 34 and is engageable with the lower end of the guide 36 to limit the upward movement of the rod and the plunger 30. An adjustable stop collar 38 is arranged on the projecting portion of the rod 34 and is engageable with the upper end of the guide 36 to limit the downward travel of the rod and the plunger 30 to determine or limit the quantity of fluid discharged at each operation. The stop collar 38 may be releasably secured in the selected position by a clamp screw 39. The stop collar 38 may be adjusted along the rod 34 to any selected position and then locked in place by the screw 39 to provide for the discharge of any selected quantity of fluid by the means 13 at each operation. A suitable handle 40 is fixed to the upper end of the plunger 30 to facilitate the manual operation of the pump means 13. It is to be observed that the upper end of the guide 36 is some distance above the handle 16 so that the engagement of the stop collar 38 with the guide 36 cannot pinch the operator's hand grasping the handle 16.

The interior of the tubular plunger 30 is in communication with the upper portion of the body 10 and the container 11. One or more ports 41 are provided in the upper portion of the plunger 30 to place the interior of the plunger in communication with the upper body section 14 and the container 11. The pump means 13 further includes an inlet valve or traveling valve 42 controlling communication between the interior of the tubular plunger 30 and the pump chamber C. The valve 42 may be a conical plug-like element adapted to partially enter the lower end of the plunger 30 to seal with the lower inner edge of the plunger. Spring means controls the

valve 42. A helical extension spring 43 is connected between the valve 42 and a suitable part of the plunger structure. In the preferred construction illustrated the upper end of the spring 43 is secured to an eye 44 on the lower end of the rod 34 and the lower end of the spring is secured to a rod or stiff wire 45 which, in turn, is connected with the valve 42. The lower portion of the wire 45 may be soldered or otherwise fixed in an opening 46 in the upper end of the valve 42 and with the spring 43 it forms a valve support that is yieldable to permit opening of the valve during the upstroke of the plunger 30.

The pump means 13 further includes a foot valve or discharge valve 47 for controlling the discharge of fluid from the chamber C and for preventing the entrance of soil and other solid matter to the chamber during the upstroke of the plunger 30. The valve 47 may be in the nature of a ball seating upwardly against the lower end of the member 12 to close its passage 24. The ball 47 is contained in the socket 25 of the tip 23 and is urged to its closed position by an helical spring 48 arranged under compression between the valve and the lower wall of the socket 25. During the down stroke of the plunger 30 the valve 47 opens to allow the fluid to discharge through the socket 25 and the ports 26.

Fig. 3 illustrates an optional or modified form of construction. In this case the body 10^a comprises two elongate tubular sections 14^a and 15^a corresponding in location and function to the above described sections 14 and 15. The sections 14^a and 15^a have thin-walled telescopically related end portions 50 and 51, respectively. The portion 50 extends downwardly into the portion 51 so that its lower end forms a shoulder in the section 15^a. An internal upwardly facing shoulder 52 occurs on the member 15^a in spaced relation to the lower end of the portion 50. A split clamp 53 is engaged about the portion 51 and is adapted to be actuated or tightened by a screw 54 to clamp the portion 51 onto the portion 50. A packing assembly is arranged in the section 51 to seal about the plunger 30. This packing assembly may comprise metal rings 32^a arranged against the lower end of the portion 50 and the shoulder 52 and a tubular body of packing 33^a arranged between the rings to seal about the plunger 30. The packing means may be adjusted or tightened by loosening the screw 54 and then driving the section 14^a downwardly with respect to the section 15^a by striking the handle 16. Following this compression of the packing 33^a the screw 54 is tightened to again rigidly connect the body sections 14^a and 15^a.

In use or operation the fluid to be employed is poured into the container 11. Where the device is to be used for weed eradication carbon bisulphide or a similar liquid may be provided in the container 11 and where the device is to be used in the fertilization of plants a suitable liquid fertilizer is provided in the container 11. The stop collar 38 may be adjusted along the plunger rod 34 and locked in position by the clamp screw 39 to provide for the discharge of the liquid in any selected quantity. For example, the stop collar 38 may be set to cause the pump means 13 to discharge about two ounces of the liquid with each operation. The screw 29 may be backed off and the stop 27 may be adjusted along the member 12 to condition the device for the injection of the liquid at any selected depth below the ground surface. The device is then in condition for operation.

To operate the device the needle-like member 12 is thrust or forced into the soil. This may be done by pushing downwardly on the handle 16 and by pressing on the stop 27 with the foot. The stop 27 is adapted to engage the ground surface to limit the downward movement of the member 12 and thus locate the discharge ports 26 a given distance from the ground surface. Assuming that the plunger 30 is in its up position and that the device is primed, the handle 40 is then grasped and a downward force is put on the plunger rod 34 to drive the plunger 30 downwardly. Downward movement of the plunger 30 through the chamber C results in the displacement of fluid from the chamber through the passage 24, the socket 25 and the ports 26. The valve 42 is closed during the down stroke of the plunger 30 and the valve 47 opens when the pressure in the chamber C increases with the downward stroke of the plunger. The plunger 30 is moved downwardly until the collar 38 engages against the guide 36 to limit the down stroke. The stroke of the plunger 30 is thus limited so that a given quantity of the liquid or fluid is injected into the soil. It will be observed that the fluid is forced into the soil under a substantial pressure so that it penetrates the soil even in cases where the soil is packed or hard. The plunger 30 is then moved to its up position to recharge the chamber C. During the upstroke of the plunger 30 the valve 47 is closed and the valve 42 opens to allow the free flow of the fluid through the plunger into the chamber C. The above operations may, if desired, be repeated to force several charges of the fluid into the soil. When the operations are completed the member 12 is pulled from the ground so that the device may be carried to another location for operation.

Having described only typical preferred forms and applications of our invention we do not wish to be limited or restricted to the specific details herein set forth, but wish to reserve to ourselves any variations or modifications that may appear to those skilled in the art or fall within the scope of the following claims.

Having described our invention, we claim:

1. A device for injecting fluid into the soil including a tubular body, a packing held on a stationary abutment in the body, a container secured to the body to be in communication with the upper part of the body, a needle member on the lower end of the body adapted to be forced into the soil and having a discharge port leading from the body, an elongate tubular plunger reciprocable in the body through the packing, the exterior of the plunger being uniform in diameter throughout its length to fit the packing and the plunger having its upper end in communication with the body above the packing, a valve for closing the lower end of the plunger and adapted to open upon the development of reduced pressure in the lower portion of the body, a spring within the plunger for yieldingly urging the valve to its closed position, a rod projecting from the body for operating the plunger, and an inwardly closing check valve controlling said port.

2. A device for injecting fluid into the ground comprising an elongate body including two tubular sections, means connecting adjacent ends of the sections for relative longitudinal adjustment, a needle member on the lower end of the lower body section adapted to be entered in the soil and having a port for the discharge of fluid, a container carried by the upper body section to supply fluid thereto, an elongated tubular plunger re-

ciprocable in the body, packing means arranged between opposing faces on the sections below the point at which fluid is supplied to the plunger to seal about the plunger and compressed by said adjustment of the sections, a downwardly opening valve controlling flow through the plunger, an extensible spring in the plunger for closing the valve, and a downwardly opening spring-held valve closing said port of the needle member.

10 3. A device for injecting fluid into the ground comprising an elongate body including two tubular sections, means connecting adjacent ends of the sections for relative longitudinal adjustment, a needle member on the lower end of the lower body section adapted to be entered in the soil and having a port for the discharge of fluid, a container carried by the upper body section above the connecting means to supply fluid to the upper portion thereof, an elongated tubular plunger reciprocable in the body, packing means arranged between opposing faces on the sections to seal about the plunger and compressed by said adjustment of the sections, a downwardly opening valve engaging the lower end of the plunger controlling flow through the plunger, a spring acting under tension between the valve and a fixed part adjacent the upper end of the plunger and urging the valve closed, a spring-held check valve controlling said port, a rod on the plunger projecting from

the upper end of the body, an operating handle on the rod, and a handle on the upper end of the body.

4. A device for injecting fluid into the soil including a tubular body, a packing held on a stationary abutment in the body, a container secured to the body to surround the upper portion thereof and having communication with the body at a point above the packing, a needle member on the lower end of the body adapted to be forced into the soil and having a discharge port leading from the body, a tubular plunger operable in the body in engagement with the packing to displace charges of fluid from the body through said port, the plunger being of uniform external diameter to slidably fit the packing throughout the length of its stroke and being open at its upper end to receive fluid from the upper part of the body and being formed with an open lower end to discharge fluid into the body below the packing, a valve for closing the lower end of the plunger, a tension spring connected between the valve and a fixed part adjacent the upper end of the plunger normally holding the valve closed, and a rod on the plunger extending from the body for operating the plunger.

CLARENCE H. McDANIEL.
